UNITED STATES PATENT OFFICE

ERNEST H. PAFFRATH, OF ST. LOUIS, MISSOURI

SEWER INLET

Application filed October 19, 1929. Serial No. 400,787.

This invention relates generally to sewer inlets and more specifically to concrete sewer inlets of sectional form, the predominant object of the invention being to provide a 5 sewer inlet comprised of a plurality of sections formed of concrete or similar material which may be assembled within a sewer opening to provide a concrete sewer inlet of great durability.

10 Figure 1 is a plan view of my improved sewer inlet.

Figure 2 is a vertical section taken on line 2—2 of Figure 1.

15 Figure 3 is a cross section taken on line 3—3 of Figure 2.

Figure 4 is a cross section taken on line 4—4 of Figure 2.

Figure 5 is a fragmentary section taken on line 5—5 of Figure 3.

20 In the drawings, wherein is shown for the purpose of illustration, merely, one embodiment of the invention A designates my improved sewer inlet, which comprises a bottom member 1 formed of concrete or similar material, said bottom member preferably being

25 round in plan and being provided in its top face with a marginal recess 2 the inner wall of which serves as an annular shoulder 3 (Figure 2). Supported upon the bottom member 1 is a lower cylindrical inlet portion 4 which comprises a pair of semi-cylindrical elements 5 and 6 (Figure 4) formed of concrete or similar material. The lower cylindrical portion 4 is seated at its lower end in

30 the marginal recess 2 formed in the top face of the bottom member 1, and the inner face of said cylindrical portion contacts with the annular shoulder 3 at the inner end of said recess. The semi-cylindrical elements 5 and 6 are joined together along the contacting edges 7 of said elements (Figure 4) by means of suitable bonding material such as stiff mortar, and to facilitate the making of a secure joint between said elements at these points I

40 provide each thereof with a substantially V-shaped groove 8 which extends longitudinally of each edge 7 from end to end thereof. The V-shaped grooves 8 of the semi-cylindrical elements 5 and 6 are so positioned that the 45 grooves of the associated semi-cylindrical ele-

ments are brought into registration with each other when the elements 5 and 6 are assembled to provide rectangular openings as shown in Figure 4 and these rectangular openings are filled with bonding material when the elements 5 and 6 are secured together to provide a secure joint. The cylindrical portion 4 is also secured by suitable bonding material to the bottom member 1.

Disposed above the cylindrical portion 4 60 of the sewer inlet A and supported on the upper edge thereof is an intermediate cylindrical portion 9. The cylindrical portion 9 is constructed and arranged just as is the cylindrical portion 4; that is to say the portion 9 65 is comprised of a pair of semi-cylindrical elements 10 and 11, and these elements are provided at their contacting edges with V-shaped grooves which provide rectangular openings 12 in which bonding material is arranged to 70 provide a secure joint between the associated elements 10 and 11.

The cylindrical portion 9 at its lower edge is secured by suitable bonding material to the upper edge of the cylindrical portion 4. 73 The joints between the elements 5 and 6 are offset horizontally with respect to the joints between the elements 10 and 11.

Mounted on the upper edge of the cylindrical portion 9 is the top member 13 of my 80 improved structure, said top member comprising a pair of elements 14 and 15 which are so associated with each other as to provide a substantially U-shaped member (Figure 3). Each of the elements 14 and 15 includes a 85 straight portion 16 and a curved portion 17, and at the contacting edges 18 of said elements, each thereof is provided with a substantially V-shaped groove, and these grooves are combined when the sill is assembled to 90 provide a rectangular opening 18' in which suitable bonding material is arranged to provide a secure joint between said elements 14 and 15. The outer end of the portion 16 of each of the elements 14 and 15 is provided 95 with a recess 19 shaped to receive a sill 20 (Figure 2), said sill being extended across the space between the outer ends of the portions 16 of the respective elements 14 and 15. The sill 20 is secured in the recesses 19 by suit- 100

able bonding material and as shown in Figures 2 and 3 said sill at its approximate center rests upon a portion of the top edge of the cylindrical portion 9, to which top edge portion said sill is secured by bonding material.

Because of the difference in the cross-sectional shape between the top member 13 and the cylindrical portion 9, substantially triangular shaped spaces 21 are present at opposite sides of the mouth portion of the top member 13 as shown by dotted lines in Figure 1. Such spaces, of course, would be objectionable and I eliminate same by the use of substantially triangular shaped sections of material 22 which cover the spaces referred to. The sections of material 22 rest upon portions of the top edge of the cylindrical portion 9 and said sections of material are secured to the top edge of the cylindrical portion 9 the portions 16 of the elements 14 and 15 of the top member 13 and the sill 20, by suitable bonding material. By referring to Figure 5 it will be noted that the sections of material 22 are inclined downwardly and inwardly so as to cause water to flow thereover into the interior of the sewer inlet A.

23 designates the inlet stone or cap which rests upon the top member 13, said stone or cap being secured in place by suitable bonding material and being provided with an opening 24 formed therethrough which is closed by a closure element 25.

The element 6 of the cylindrical portion 4 is provided with an aperture 26 formed through the wall thereof which received the end of a pipe 27 with which a trap 28 of ordinary design is associated, said trap being closed at one end thereof by a closure element 29 and connected at its other end by a pipe 30 to the sewer (not shown). It is obvious that a trap will not be associated with the sewer inlet in every case, and when no trap is employed the aperture 26 will be omitted.

45 In the use of my improved sewer inlet the various parts thereof, all of which, with the exception of the closure element 25 and the trap 28 and pipe 27, are formed of concrete or similar material, are taken to the location 50 of the sewer inlet where said parts are assembled within the sewer opening in the ground to provide a concrete sewer inlet. The various elements of which the sewer inlet is comprised are securely joined together by 55 suitable bonding material hence what amounts to an integral structure is provided.

I claim:

1. A sewer inlet comprising a plurality of elements formed of concrete or similar material including a substantially cylindrical inlet portion arranged within the sewer opening longitudinally thereof, said cylindrical inlet portion being comprised of a bottom, a lower cylindrical section, and an intermediate cylindrical section, said lower cylindrical

section and said intermediate cylindrical section being each formed of a plurality of semi-cylindrical elements secured to each other and to the elements of the associated cylindrical section to provide a unitary structure and a substantially U-shaped top member supported by said intermediate section at the top thereof, said top member being comprised of a plurality of elements secured together, and a sill which is in the form of a separate element secured in place in the structure of the top member and partially closes the open portion thereof.

2. A sewer inlet comprising a plurality of elements formed of concrete or similar material including a substantially cylindrical inlet portion arranged within the sewer opening longitudinally thereof, said cylindrical inlet portion being comprised of a bottom, a lower cylindrical section and an intermediate cylindrical section, said lower and intermediate sections being each formed of a plurality of semi-cylindrical elements secured to each other and to the elements of the associated cylindrical section to provide a unitary structure, a substantially U-shaped top member supported by and secured to said intermediate cylindrical section at the top thereof, said top member being comprised of a plurality of elements secured together, a sill secured to said top member, substantially triangular shaped elements arranged to close spaces between portions of said intermediate cylindrical section and said top member, an apertured top stone supported by said top member, and a closure element for closing the aperture in said top stone.

In testimony that I claim the foregoing I hereunto affix my signature.
